CLOCK

Martin J. Ferber, New York, N. Y.

Application September 26, 1956, Serial No. 43,095

Term of patent 14 years

(Cl. D42—7)

Fig. 1 is a perspective view of a clock, showing my new design;

Fig. 2 is a vertical sectional view taken on the line 2—2 of Fig. 1; and

Fig. 3 is a rear elevational view.

I claim:

The ornamental design for a clock, as shown.
